UNITED STATES PATENT OFFICE.

FRANK KNOBELOCH, OF DAYTON, OHIO, ASSIGNOR TO THE KINNARD MANUFACTURING COMPANY, OF SAME PLACE.

BOX.

SPECIFICATION forming part of Letters Patent No. 634,647, dated October 10, 1899.

Application filed February 18, 1899. Serial No. 706,045. (No model.)

To all whom it may concern:

Be it known that I, FRANK KNOBELOCH, a citizen of the United States, residing at Dayton, county of Montgomery, and State of Ohio, have invented certain new and useful Improvements in Boxes, of which the following is a full, clear, and exact description, reference being had to the accompanying drawings, forming part of this specification.

My invention relates to an improvement in boxes or packages designed more particularly for shipping fragile goods—such as lamp-chimneys, lamp-globes, and the like—which are usually now shipped by packing in hay or straw. To pack these articles in the ordinary way is expensive, is attended with much risk, and makes a heavy awkward package, whereas by means of my improvement they are packed for shipment with safety, economy, and in a light convenient package.

In the drawings, Figure 1 is a plan view of the blank cut and scored in the proper manner. Fig. 2 is a top plan view showing the flaps folded back. Fig. 3 is the same with two of the flaps folded into position. Fig. 4 is a top plan view of the box with the flaps in position. Fig. 5 is a plan view of the blank cut in a slightly-different manner. Fig. 6 is a sectional view showing a globe packed in this latter form of a box.

The blank is shown in Fig. 1 cut and scored in the desired manner, the scores being shown by the dotted lines. The scores $a a a a$ and $b b$ determine, respectively, the width and length of the sides $A A A' A'$. The sides are provided with end flaps $B B C C$ and $B' B' C' C'$. The alternate flaps $B B$ and $B' B'$ have tongues $D D$ and $D' D'$, adapted to fold along the scores $d d$ and $d' d'$. The other flaps $C C' C'$ have slotted tongues $E E E' E'$, said slots being of a width slightly greater than twice the thickness of the cardboard. Said slotted flaps are adapted to fold along the scores $e e e' e'$. The width of these tongues is such that they will fit snugly against the inside of the article to be shipped. The flaps $B B B' B'$ are provided with slots $g g g' g'$ at the middle, beginning at the scores $d d d' d'$ and extending inwardly parallel to the length of the box and being of a length that will en-

able them to admit one leg of the slotted tongues $E E E' E'$.

The blank is provided with a flap J , which is for the purpose of gluing or otherwise fastening the two opposite sides $A A'$ together. 55

In folding the box the sides are folded at right angles along the scores $a a a a$ and the flap J is glued or otherwise fastened to the edge of the side A' , as shown in Fig. 2. Next the flaps $B B$ are folded down along the scores $b b$, the tongues $D D$ at the same time being folded bodily inward along the scores $d d$, as shown in Fig. 3. Then the flaps $C C$ are folded down along the scores $b b$ over the flaps $B B$, the slotted tongues $E E$ being at the same time folded along the scores $e e$ and inserted bodily through the slots $g g$, thus locking the flaps together.

A modified form of the blank is shown in Fig. 5. The only differences are that the flaps $C C' C' C'$ are extended the full length of the tongues $E E E' E'$ and the flaps $B B' B'$ are extended nearly the length of the tongues $D D' D'$, the scores, however, in the latter case extending completely across the flaps. 75

The lamp-chimney, globe, or other article to be packed will rest directly against the top and bottom of the box in first form of box shown. The tongues protruding inward and bearing against the inside of said globe, &c., 80 will prevent its movement from side to side. The sides are thus protected from banging, and the only place it can receive a blow is at the bottom or top, and as it is strongest in the direction of its length it is not likely to be broken in the ordinary handling. Such a globe, however, as is shown in Fig. 6, is more perishable, and in order to render such a globe additionally secure I prefer to use diaphragms $P P$, (such as is described in my 90 other application, No. 706,043, of even date herewith,) with openings in them whose diameters are approximately the inner diameters of the openings of said globe, and when their diaphragms are used the form of blank 95 shown in Fig. 5 is the preferable one. The sides of the diaphragm are then made of the same depth as that of the extended portions $G G G' G'$ of the flaps $B B' B'$. These flap extensions $G G' G' G'$ are folded bodily in- 100

ward and their edges bear upon the diaphragm, thus bracing it, while the tongues D D' D' project through the opening in the diaphragm and bear against the inner walls 5 of the globe. The globe is thus protected at the top and bottom as well as at the sides, the tongues preventing its movement from side to side and the diaphragms, strengthened by the flap extensions, holding it in place vertically.

Having thus described my invention, what I wish to secure by Letters Patent is—

1. A box made from a blank having sides and end flaps, integral with said sides, two of 15 the alternate flaps having tongues adapted to fold bodily inward, and slots in the middle of said flaps, each of the other two flaps having slotted tongues adapted to be thrust bodily through said slots, thus locking the flaps together, substantially as shown and described.
2. A box for shipping fragile articles having sides and end flaps, integral with said sides, two of the alternate flaps having flap 25 extensions provided with tongues, said flap extensions being adapted to fold bodily inward, said flaps also having slots, the other two flaps having slotted tongues adapted to

be thrust bodily through said slots and lock the flaps together, and serving to brace against the inner edges or surface of the article to be shipped, substantially as and for the purpose described. 30

3. A box for shipping fragile articles, having sides and end flaps integral with said sides, two of the alternate flaps having flap 35 extensions provided with tongues at their outer edge, said flap extensions being adapted to fold bodily inward, said flaps also having slots, the other two flaps having slotted tongues adapted to be thrust bodily through 40 said slots and lock the flaps together, and a diaphragm having a main flat portion provided with an opening, and sides at an angle to said main flat portion adapted to brace against the walls and end of the box, said 45 diaphragm being strengthened by said flap extensions, the flap extensions, tongues and diaphragm together serving to brace and hold the article in place, substantially as and for the purpose described.

FRANK KNOBELOCH.
